UNITED STATES PATENT OFFICE.

JOHN H. BROWN, OF BROOKLYN, NEW YORK.

BUTTON-HOLE SEWING-MACHINE.

SPECIFICATION forming part of Letters Patent No. 225,559, dated March 16, 1880.

Application filed November 11, 1879.

To all whom it may concern:

Be it known that I, JOHN H. BROWN, of Brooklyn, Kings county, in the State of New York, have invented certain new and useful 5 Improvements relating to Button-Hole Sewing-Machines, of which the following is a specification.

I obtain the required motion by very simple mechanism. The same machine may be used 10 for ordinary sewing with changes of some of the parts.

I employ a lever peculiarly mounted, and operated by a cam, to perform the important function of shifting the position of the goods 15 to enable the needle to strike alternately outward and inward around the button-hole. A separate cam is employed to shift the sewing from one side to the other of the button-hole, and still another cam to give the proper longitudinal feed.

The accompanying drawings form a part of this specification, and represent what I consider the best means of carrying out the invention.

25 Figure 1 is a plan view of a sewing-machine having my invention applied thereto, with the goose-neck and its connections removed. Fig. 2 is a side view of the same, with a portion broken away. Fig. 3 represents a section 30 through a portion on line *y*/*y* in Fig. 1. Fig. 4 is a section on line *z*/*z* in Fig. 1.

Similar letters of reference indicate like parts in all the figures.

35 A is the fixed frame of the sewing-machine, which may be of cast-iron. I have in my experiments used the style and size known as "Wheeler & Wilson, No. 7."

It will be understood that the machine has 40 all the parts for properly operating the needle and hook, with the respective threads for each.

B is the driving-shaft. I provide it with a worm, B', and beveled-gear wheel B'', by which my attachment is operated.

45 The garment is previously prepared by cutting the button-holes as plain slits in the fabric, and I clamp the fabric for each button-hole successively between plates, which, having a sufficient aperture at and around the 50 button-hole, effect the feeding, while the needle reciprocates in a uniform line, as in com-

mon sewing-machines. The clamp is marked P, and is opened and closed by turning a lever, O. The clamp is fixed on a slide, N, which is capable of moving longitudinally in 55 a groove formed in a carriage, M. Both are operated by cams.

The worm B' engages with a worm-wheel, D', on an upright shaft, D, which carries a disk provided with a heart-shaped grooved 60 cam, D'', which is engaged by a pin, M'', and by its slow rotation gives to the carriage M the gradually-sliding motion required to shift the clamp P and the fabric carried thereby lengthwise of the button-hole the required 65 amount for each stitch.

The beveled-gear wheel B'' engages with a larger beveled-gear wheel, E', on an upright shaft, E, which carries at its upper end a cam, E''. This cam turns once for every two reciprocations of the needle. (Not shown.)

G is a lever, peculiarly formed and operated. It has no fixed center. A transverse slot, *g*, formed in the arm *x* serves as a guide longitudinally by fitting upon a pin, *f*, fixed in the 75 lever G. The cam E'' acts against the side of the lever immediately adjacent to this slot, and at each revolution moves said lever. At one end is swiveled a bearing-piece, H, which acts against a shoulder, N', on the slide N, 80 and moves the slide with the connected fabric in opposition to the stress of a spring, I, mounted in the carriage M, which spring, as the cam E'' retires, induces the return motion of the slide. This reciprocation of the slide 85 N at each two reciprocations of the needle induces the proper movements of the fabric relatively to the needle to produce a button-hole stitch.

At the other end of the lever G, I fix a bearing-piece, J, which is adjustable by means of a screw, *j*, and presses against the cam D''' on the shaft D. This cam is simple in form. It has two offsets. When these, by the slow rotation of the shaft D, successively pass the 90 bearing-piece J they change the position of the latter. It follows that, considering the bearing-piece J as the fulcrum of the lever G, it is a shifting fulcrum. It stays a while in one position, and thus conditioned the shifting motion of the goods due to the action of the cam E'' produces the required stitch along 95 100

one side of the button-hole. Then, when the end of the button-hole is reached, the offset in the cam D^3 changes the position of the fulcrum J , and consequently induces the lever 5 G to reciprocate in a new position—*i. e.*, a position in which the slide N is located—so as to bring the stitch on the other side of the button-hole during the return motion.

I make the cam E^2 of such shape as will 10 give more motion to the lever G than is ordinarily required, and control the amount of motion by a set-screw, K , which is tapped through the lower part of the lever G , and at each reciprocation comes to rest against a 15 boss, A' , forming a part of the fixed framework of the machine. It follows that the cam E^2 thrusts the adjacent surface of the lever G always to a uniform point; but as the cam E^2 retires the lever G does not follow it to the 20 full extent allowed by the cam, but is arrested at a certain point by the set-screw K . This varies the extent of the movement of the slide 25 N , and consequently the length of the lateral stitch.

The adjustment of the bearing-piece J is 25 only necessary in first setting the machine at work on any given size of button-hole, and to compensate for subsequent wear. The parts are little liable to wear or derangement.

Nearly or quite all the ordinary improvements and modifications may be applied to 30 the other parts of the machine in connection with my attachment.

I claim as my invention—

The lever G , having steadyng-pin f , arm x , 35 having the slot g , cams $E^2 D^2 D^3$, carriage M , slide N and its attachments $O P$, the shafts $D E$ and their operating mechanism, and the spring I , all combined and operating as and for the purposes set forth.

In testimony whereof I have hereunto set 40 my hand this 20th day of October, 1879, in the presence of two subscribing witnesses.

JOHN H. BROWN.
